INVENTOR.

J. D. Howell

BY

W. M. Monroe

ATTORNEY.

UNITED STATES PATENT OFFICE.

JOSHUA D. HOWELL, OF PORTERVILLE, CALIFORNIA.

WATCHMAKER'S TOOL.

Application filed March 29, 1922. Serial No. 547,719.

To all whom it may concern:

Be it known that I, JOSHUA D. HOWELL, a resident of Porterville, in the county of Tulare and State of California, a citizen of the United States, have invented certain new and useful Improvements in Watchmakers' Tools, of which the following is a specification.

My invention relates to improvements in watchmakers' tools and refers particularly to a tool or implement employed in the setting or mounting of jewels, and the main object of my invention is the provision of a tool which will permit the workman to perform the operation of jewel setting in a rapid and perfect manner, and thus provide a highly useful, desirable and efficient tool of this character.

Another object of my invention is the provision of a tool of the character and for the purpose stated which will be of small size, which can be easily supported upon the bench and dispose the parts to be operated upon in the most desirable position, which can be instantly adjusted to the work, and which can be manufactured at such a low price as to make its use practically necessary.

To attain the desired objects my invention consists of the jewel-setting tool herein shown, described and particularly defined and distinguished by the claims, the right to make any changes which come within the scope of said claims being reserved.

In order that the construction in detail and the manner of using my device may be understood and its many advantages be appreciated, I invite attention to the accompanying drawings, in which:

Figure 1 represents a side elevation of the complete tool for setting jewels constructed according to my invention.

Fig. 2 represents a top plan view of the tool.

Fig. 3 represents a sectional view on the line 3—3 of Fig. 2.

Fig. 4 is a front or face view of the clamping member or disc of my device.

Fig. 5 is a view on the line 5—5 of Fig. 3, and

Fig. 6 is a side elevation of the complete device showing the manner of operation and use.

The tool is of extremely simple construction and consists of the handle or grasping portion 1, which is made preferably of wood

or other heat non-conducting material, and of the proper size and shape, having mounted therein the metal guiding sleeve 2, which receives and guides the tubular stem 3, which carries at its inner end the holding or clamping head or disc 4, provided with an opening 5 to receive the air-spring stud carried by the usual balance wheel 6, and said disc clamps the balance wheel against the open or loop-shaped portion 7, of the inclined disposed heat-conducting member 8, which is secured rigidly to the heating head 9, forming a part of the supporting arm 10, which rests upon the bench 11, and is formed with a band or collar 12, fitting upon the reduced inner end 13, of the handle or grasping portion, this comprising the entire structure and showing the balance wheel in position to operate upon its jewel.

From the foregoing description, taken in connection with the drawing, the operation or manner of using my invention will be readily understood and it will be noted that the device in operative position assumes the attitude shown in Fig. 6, with the balance wheel in position shown and this permits the operator to place one hand upon the handle and allows free operation of his other hand in the operation of setting the jewel in the shellac, as is usual, and also permits the head and heat-conductor to be thoroughly heated in the manner desired, all of which will be readily understood by the watchmaker or others skilled in the art of jewel setting.

It will be at once apparent that I provide a small, compact, simple and inexpensive tool for setting jewels, which can be easily supported in the most advantageous position, which will permit the operator to use both hands, which will dispose the parts to be operated on where they are freely accessible, which can be instantly adjusted to hold the parts in the desired position, which will properly receive and distribute the heat, and which in every particular will prove useful, desirable, practical and efficient.

A most important advantage is gained from the construction of my device, by reason of the fact that the tool is supported upon the bench at an incline, the handle having its outer end resting on the bench, the inner portion of the heat-conducting portion also resting on the bench, and the heat-receiving head being supported above

and away from the bench where it can be easily heated without danger of burning the bench or the hand of the user.

I claim:

- 5 1. A watchmaker's tool of the character and for the purpose described, consisting of a handle or grasping portion adapted to have its outer end rest on the bench to support the tool in an inclined position, a heat-receiving and supporting portion connected to the handle and consisting of a band engaging the handle and an integral depending vertically disposed arm, an adjustable holding means mounted on the handle for
- 10 securing the work between said handle and supporting portion, said heat-receiving and supporting portion consisting of an arm adapted to have its inner portion rest on the bench, a head formed on the outer end of
- 15 said arm to receive the heat and arranged above the bench, and a member connected at its outer end to said head projecting inward and having a transversely arranged loop at
- 20

its inner end disposed near the jewel receiving portion of the part operated upon, said loop having its closed portion arranged to support the jewel receiving portion.

2. A watchmaker's tool of the character and for the purpose described, consisting of a handle having an opening extending therethrough, a stem arranged in said opening with its outer end projecting beyond said handle, a clamping head carried by the inner end of said stem, an arm secured to the handle, having a portion to rest on a support, and a head disposed at the outer end of said arm, and a member having its outer end secured to said head and having at its inner end a loop, the closed portion of which is arranged parallel to the clamping head and cooperating therewith to support the work.

In testimony whereof I hereunto affix my signature.

JOSHUA D. HOWELL.
